UNITED STATES PATENT OFFICE.

EDWARD F. SHERRICK, OF LOS ANGELES, CALIFORNIA.

CARBURETOR.

Application filed October 27, 1920. Serial No. 419,894.

This invention has to do with a carburetor for internal combustion engines and the like, and an object of the invention is to provide a simple, effective and efficient device of that character.

The various objects and features of the invention will be best and more fully understood from the following detailed description of a typical preferred embodiment of 10 the invention throughout which reference is had to the accompanying drawings, in which—

Fig. 1 is a vertical section through the carburetor; Fig. 2 is a vertical section 15 through the carburetor, being a view taken as indicated by line 2—2 on Fig. 1; Fig. 3 is a horizontal section of the carburetor being a view taken as indicated by line 3—3 on Fig. 1; and Fig. 4 is an enlarged detailed 20 section taken as indicated by line 4—4 on Fig. 2.

Throughout the drawings numeral 10 designates the body portion of the carburetor in connection with which is a float chamber 25 11 and an outlet 12. The body 10 is preferably cylindrical in form and is disposed so that its longitudinal axis is horizontal. One end of the body 10 is closed by an end plate 13 secured to the body 10 by suitable screws 30 14 while the other end of the body 10 communicates with the outlet 12 which is adapted to be connected to the intake of the engine or apparatus on which the carburetor is being employed.

35 Along each side of the body 10 there is arranged an air intake manifold 15. Each of the manifolds 15 is provided with a plurality of parallel vertical partitions 16 which divide it into a plurality of ducts or ports 17. 40 It will be noticed from inspection of the drawings that the ports 17 are open at their outer ends and that they open at their inner ends directly into the interior of the body 10. Further it will be noticed, particularly 45 in Fig. 2 of the drawings, that the ports 17 are larger, or of greater capacity, at their outer ends than they are at their inner ends where they communicate or connect into the body 10. It is obvious how a reduction of pressure in the outlet 12, due to the action of the 50 engine on which the carburetor is installed, will cause air to be drawn into the body 10 through the ports 17. The shape of the ports 17 causes the air passing through them 55 to increase in velocity as it approaches their inner ends and to reach its highest velocity at

the point where it issues into the body 10. This variation in velocity through the ports 17 is accompanied by a variation in pressure at various parts of the ports; the pressure at 60 the outer portions of the ports 17, being greater than it is at the inner portions of the ports 17.

In accordance with the present invention a jet or tube 20 extends upwardly from the float 65 chamber 11 into each port 17 in the manner clearly shown in Fig. 2 of the drawings. The tubes 20, it will be noted, extend upwardly and slightly into the ports 17 at the extreme inner ends of the ports 17. Liquid 70 fuel is maintained in the tubes 20 so that it will be drawn from them by the air being drawn through the ports 17 by the engine, thereby causing a mixture of liquid fuel and 75 air to issue into the body 10 from whence it passes into the outlet 12. The fact that the air at the inner ends of the ports 17 is at a comparatively low pressure and is moving at a high velocity causes the liquid fuel 80 which is drawn from the tubes 20 to be very effectively and thoroughly broken up or atomized.

The float chamber 11 which I have illustrated in the drawings is airtight and comprises a cup-like member 21 secured to a flange 22 formed on the under side of the body 10. A fuel supply pipe 23 is connected into the cup-shaped member 21 and a constant level of liquid fuel is maintained 85 in the cup-shaped member 21 by a needle 90 valve 24 arranged to be operated by a suitable float mechanism 25. It will be understood, of course, that the float chamber and the parts in connection therewith may be of any suitable design and construction and 95 that the present invention is in no way limited or restricted to the specific design or construction herein set forth.

The tubes 20 which extend into the ports 17 extend downwardly into the liquid carried in the float chamber, as clearly shown in Fig. 2 of the drawings. Liquid from the float chamber stands in the tubes 20 at a level where it will be properly drawn from the tubes 20 by the action above described. A 100 pipe 30 connects into the outer portion of one of the ports 17 and connects into the upper portion of the float chamber. The difference in pressure between the outer portion of the tube 17 and the inner portion 105 of the tube 17 will determine the level of liquid in the tubes 20. In order that the 110

level of liquid in the tubes 20 may be adjusted to be at the desired height an adjusting screw 31 is carried in the outer portion of the port 17 into which the pipe 30 is connected. The screw 31 is adapted to be adjusted to vary the size of the outer portion of the port 17. In practice the screw 31 may be very easily and conveniently adjusted to cause the liquid to stand at the proper level in the tube 20. The pressure in the float chamber is ordinarily less than atmospheric because of the fact that the air has considerable velocity and is at a reduced pressure at the point where the pipe 30 connects into the port.

In order to control the amount of mixture admitted into the body 10 and to cause the ports 17 to handle a certain volume of air the valve 40 is arranged in the body 10 and is adapted to be actuated or positioned to allow only the proper number of ports 17 to communicate with the interior of the body 10. The valve 40 is a drum-shaped structure carried on a suitable shaft 41 supported in bearings 42 and 43. The valve 40 accurately fits the interior of the drum 10 and is formed with two substantially diametrically opposite openings 44. It will be seen from inspection of the drawings that the openings 44 are substantially triangular shaped and are arranged so that their long edges extend across and around the valve. The long edges of the openings are preferably shaped as shown in the drawings. From inspection of the drawings it will be readily understood how the valve 40 may be rotated in the body so that any desired number of ports 17 will be in communication with the interior of the body 10. In the preferred form of construction the openings 44 are formed in the valve 40 so that the ports 17 will be opened or closed alternately on one side of the body 10 and then the other when the valve is rotated.

In accordance with the present invention the valve 40 is automatically operated to open and close the ports 17 so that for any speed of operation there will be just a sufficient number of ports 17 open to handle the required amount of air at a certain velocity. In other words, the invention provides means whereby the ports 17 are opened and closed so that all of the ports in operation always operate under certain predetermined conditions, that is with respect to velocity and pressure of air, thus causing the carburetor to deliver a uniform mixture at all speeds of operation. The regulation of the valve 40 is accomplished by connecting the upper end of cylinder 50 with the manifold 12 by means of a duct 51. A plunger 62 is carried in the cylinder 50 and is adapted to be moved in the cylinder by variations of pressure in the cylinder. A rack 53 is connected to the plunger 52 and is arranged to engage

a gear 54 mounted on the shaft 41. The weight of the various parts normally holds the plunger rack, etc. in the position shown in Fig. 1 of the drawings. With this positioning of the mechanism the valve 40 is in position to leave only one port 17 in communication with the interior of the body 10. When the throttle valve 60, which is arranged in the outlet 12, is opened allowing mixture to be drawn from the body 10 there is a reduction of pressure in the manifold 12 below the valve 60 causing a corresponding reduction of pressure in the cylinder 50. This allows the atmospheric pressure on the under side of the plunger to move the plunger upwardly in the cylinder and thereby move the rack. The rack meshing with the gear 54 rotates the shaft 41 and the valve 40. The valve 40 is rotated by this action in such direction as to open more ports 17 and admit a greater amount of mixture into the body 10 to be supplied to the engine. It will be understood how regulation or positioning of the throttle valve will vary the pressure in the outlet 12 and thereby vary the position of the plunger 52 in the cylinder 50. The positioning of the plunger 52 in the cylinder 50 determines the positioning of the valve 40 and the amount of air being admitted into the body 10. By opening and closing the ports 17 with variations in speed of operation the device is regulated so that substantially a predetermined amount of air flows through each open port 17. This causes the velocity of air at any given part of any port 17 to be substantially the same at all speeds of operation causing the atomizing action to be substantially uniform in all of the ports 17 and at all speeds of operation. The fact that the atomizing action is substantially uniform and constant for all speeds of operation permits of the various parts being designed and proportioned to operate in the most efficient and effective manner.

In the preferred form of the carburetor check valves 61 are provided in the tubes 20 to prevent atmospheric pressure being communicated to the interior of the float chamber when one or more of the ports 17 are closed. The check valves 61 may be of any desired construction; for instance they may be ball check valves such as is shown in Fig. 4 of the drawings.

Having set forth only a preferred embodiment of my invention I do not wish to limit or restrict myself to any of the specific details hereinabove set forth but wish to reserve to myself any changes or variations that may appear to those skilled in the art or that may fall within the scope of the following claims.

Having described a preferred form of my invention, I claim:

1. In a carburetor having a fuel chamber,

a mixing chamber to which suction may be applied, a plurality of fuel jets to carry fuel from the fuel chamber to the mixing chamber, and a valve by means of which the several jets may be progressively cut off from or put into communication with the mixing chamber; the combination of a communication to the fuel chamber whereby a vacuum is applied thereto to maintain thereon a lowered pressure slightly above the lowered pressure applied to the jets when in communication with the mixing chamber, and checks in the jets to prevent flow of air under atmospheric pressure through them to the fuel chamber.

2. In a carburetor having a fuel chamber, a mixing chamber to which suction may be applied, said chamber having a plurality of air inlet openings, a valve by means of which the several air inlet openings may be progressively cut off from or put into communication with the mixing chamber, a fuel jet leading from the fuel chamber to each of said openings and adapted to be subjected to the vacuum in the mixing chamber when the openings are put into communication therewith; the combination of a vacuum connection between the fuel chamber and the one of said openings that is first put into communication with the mixing chamber to put a lowered pressure on the fuel chamber somewhat above the lowered pressure applied to the jet at that opening, and

checks in the jets to prevent flow of air under atmospheric pressure through them to the fuel chamber.

3. In a carburetor having a fuel chamber, a mixing chamber to which suction may be applied, said chamber having a plurality of air inlet openings, a valve by means of which the several air inlet openings may be progressively cut off from or put into communication with the mixing chamber, a fuel jet leading from the fuel chamber to each of said openings and adapted to be subjected to the vacuum in the mixing chamber when the openings are put into communication therewith; the combination of a vacuum connection between the fuel chamber and the one of said openings that is first put into communication with the mixing chamber to put a lowered pressure on the fuel chamber somewhat above the lowered pressure applied to the jet at that opening, checks in the jets to prevent flow of air under atmospheric pressure through them to the fuel chamber, and means to controllably vary the amount of vacuum applied to the fuel chamber, said means embodying an adjustable choke in said opening from which said vacuum connection leads.

In witness that I claim the foregoing I have hereunto subscribed my name this 20th day of October 1920.

EDWARD F. SHERRICK.
